C. A. Young,

Making Coiled Springs.

N° 32,395.

Patented May 21, 1861.

Trace A. Brumell
David Heaton, Jr.

Inventor,
Charles A. Young

UNITED STATES PATENT OFFICE.

CHARLES A. YOUNG, OF PROVIDENCE, RHODE ISLAND.

IMPROVED MACHINE FOR MAKING UPHOLSTERY-SPRINGS.

Specification forming part of Letters Patent No. 32,395, dated May 21, 1861.

To all whom it may concern:

Be it known that I, CHARLES A. YOUNG, of Providence, in the county of Providence and State of Rhode Island, have invented a new and useful Improvement in Machines for Making Upholstery-Springs; and I do hereby declare that the following is a full, clear, and exact description of the same, reference being had to the annexed drawings, making part of this specification, in which—

Figure 1 is a front elevation of my improved machine. Fig. 2 is a side elevation of the same. Figs. 3 and 4 are details referred to in the course of the description.

Similar letters of reference denote like parts in all the figures.

A A is the frame and table of the machine. Upon said table, in suitable bearings formed for the purpose, are placed the shafts B B, carrying the two feeding-rolls O O. The action of the two shafts is united by means of the gears d d upon each. The same are revolved by means of the gear D, driven by gear F, to which motion and power are communicated by means of the pulley G. The feeding-rolls O O are grooved upon their face to receive and carry the wire, which is introduced between the said rolls, and thence passes to the coiling-roll R.

Between the feeding-rolls and the coiling-roll R is a stand, 1, the upper part of which serves as a rest or support to the coiling-wire as it passes from the former rolls to the latter, as shown in Fig. 1. It therefore conforms to the curve of the larger coils of the spring, to which it is most serviceable, beside having a groove, l, in the curved face for the passage of the wire, as shown in Fig. 4. The coiling-roll turns in the upper end of the rod 2, which slides perpendicularly in the sleeve K upward and downward by the action of the heart-cam n upon the point of set-screw 8.

The above-described grooved rest 1, together with the perpendicular movement of the coiling-roll R, constitute one feature of invention in my improvement in contradistinction with a horizontal movement (of the coiling-roll) approaching and retreating from the feeding-rolls without the grooved rest, which forms the subject-matter of a separate patent granted to me, the said Charles A. Young, and Solomon W. Young, September 28, 1858. As the coiling-roll (as described in the said patent) ap-

proaches the feeding-rolls horizontally, the coils of the spring are successively diminished in size, and the strain upon the wire is constantly increasing. The wire in consequence has a tendency to crowd downward between the feeding and coiling rolls and to break repeatedly. The grooved rest 1 is intended to afford that support (or bearing) to the coiling-wire at this point as will prevent this crowding down of the larger coils, and for such purpose may be successfully applied in combination with the horizontal movement of the coiling-roll. But it will be observed that the perpendicular movement of the said roll R close to the feeding-rolls, besides varying the size of the coils, also acts as a support to the outside of the coil, varying in position according to the size of the coil, so that not only is the crowding of the wire prevented but a variable support is attained, which adapts itself to the requirements of the coiling-wire. It will also be noticed that the upward movement of the coiling-roll, in diminishing the size and forming the successively smaller coils of the spring, bends the wire around and against the upper feeding-roll, the face of which serves as a support to the inside of the (smaller) coils. Finally, the proper curve is imparted to the successive coils of the spring between the feeding and coiling rolls in such a manner as will support the wire in the proper place and prevent its breaking, by means of the grooved rest 1, combined with the perpendicular movement of the coiling-roll. The relative position of the feeding and coiling rolls, and the perpendicular movement of the latter causes the coils to form above the feeding-rolls, as shown in Fig. 1, and against the guard 3. This guard is of cast or wrought iron of the peculiar form shown by Figs. 1 and 2, and is firmly secured to the frame of the machine in the position shown. At the top of said guard is an overhanging lip, S, against which the larger coils are curved and cut off when a spring is formed, by means of the shears formed by said lip S, and the cutter i, upon lever 5, as shown by Fig. 2. Said lever has a weight, T, upon one end, and this end is slowly raised during the coiling of one spring by the cam 7, acting through the medium of the rod and arm 4, sliding in the sleeve g, said cam being revolved by shaft L, thereby dropping the cutter from the lip S, between which

the large coil enters, Figs. 1 and 2, and is severed at the proper time by the descent of the weighted end of lever 5, caused by the end of the cam *f* passing from beneath the lower end of the rod 4, as seen in Figs. 2 and 3. This cutting the completed spring from the coil last formed by the coiling-roll by means of the guard 3, arranged in the position shown, and the shears 5, arranged and operating as above described, renders the cutting off of each spring certain as soon as it is completed, and forms another feature of invention in my improvement. The shaft *L* is revolved by means of the gear *I*, which is driven by gear *J* on shaft *Y*, which is driven by gear *E* from the driving-gear *F*. When it is desired to increase or diminish the size of the springs it may be done by turning the screw 8 in the rod 4, thereby raising the coiling-roll *R*, to produce a spring of smaller diameter, and lowering the roll to produce one of larger diameter.

In the operation the wire is inserted in the groove of the feeding-rolls when they are revolving, and with the several parts of the machine in the position shown in Fig. 1. The wire is carried through the groove *l* of the rest 1, thence to the coiling-roll *R*, which is in position to form the first or larger coil. As the wire passes through the rolls the cam *n* revolves in the direction shown by the arrows and raises the rod 2, and with it the coiling-roll, which diminishes regularly the diameter of the successive coils of the spring as they are

formed. When the cam *n* completes a revolution a spring, properly formed, is also completed, and the coiling-roll having returned to the position shown in Fig. 1 the cam 7 is also brought into the position shown in Fig. 3, thus letting fall the rod 4, and with it the weighted end of the lever 5, causing the shears *i* *s* to sever the completed spring from the last-formed coil. The coiling proceeds until another similar spring is formed, which is cut off in its turn, and thus the operation continues.

Having thus described the construction and operation of my improved machine, what I claim is—

1. The said grooved rest 1, in combination with the coiling-roll *R*, when the said roll has a perpendicular movement close to and passing the upper feeding-roll, for supporting the inside and outside of the coil at the proper time, in the manner substantially as herein specified.

2. The guard 3, formed and arranged in relative position with the feeding and coiling, as shown, in combination with the peculiar shears or cutting device, when the latter is operated by the force of the descending weight *T*, substantially as and for the purpose herein specified.

CHARLES A. YOUNG.
